United States Patent [19]

Sutton

[11] Patent Number: Des. 328,872

[45] Date of Patent: ** Aug. 25, 1992

[54] WINDSOCK

[76] Inventor: Gary C. Sutton, 11912 Filly La.,
North Potomac, Md. 20878

[**] Term: 14 Years

[21] Appl. No.: 629,983

[22] Filed: Dec. 19, 1990

4,730,488 3/1988 David D10/59

Primary Examiner—Kay H. Chin

[57] CLAIM

The ornamental design for a windsock, as shown and described.

DESCRIPTION

FIG. 1 is a left side perspective view of a windsock showing my new design;

FIG. 2 is a front elevational view thereof;

FIG. 3 is a rear elevation thereof;

FIG. 4 is a top plan view thereof;

FIG. 5 is a bottom plan view thereof;

FIG. 6 is a right side perspective view of a second embodiment of the windsock;

FIG. 7 is a front elevational view of FIG. 6;

FIG. 8 is a rear elevational view of FIG. 6;

FIG. 9 is a top plan view of FIG. 6; and,

FIG. 10 is a bottom plan view of FIG. 6.

The post being omitted in FIGS. 2, 3, 4, 5, 7, 8, 9 and 10

for ease of illustration.
